UNITED STATES PATENT OFFICE.

THOMAS MAYOR, OF PROVIDENCE, RHODE ISLAND.

BEARING FOR SPINDLES OF SPINNING AND TWISTING MACHINES.

SPECIFICATION forming part of Letters Patent No. 255,644, dated March 28, 1882.

Application filed May 9, 1881. (No model.)

To all whom it may concern:

Be it known that I, THOMAS MAYOR, of the city and county of Providence, and State of Rhode Island, have invented a new and useful Improvement in Bearings for Spindles of Spinning and Twisting Machines; and I hereby declare that the following is a full, clear, and exact description of the same, reference being had to the accompanying drawings, forming part of this specification.

This invention has reference to an improvement on Letters Patent No. 215,142, granted to Thomas Mayor, assignor to Joseph Mayor, May 6, 1879.

The object of the invention is to limit the oscillation of the bolster-tube supported on the ball-and-socket bearing; and it consists in the application of wire springs to this bolster, as will be more fully set forth hereinafter.

Figure 1 is a view of a bolster provided with a ball near the center of its length, to which wire springs are secured by placing the bent end of the wire in a groove made into the ball and resting the wire springs in slots at each end. Fig. 1^a is a cross-section on line *x x* of Fig. 1. Fig. 2 is a view of a bolster provided with a ball near the center of its length, to which wire springs are secured by entering the bent ends of the springs into holes made in the ball and resting the wire springs in slots at each end. Fig. 2^a is a cross-section on line *y y* of Fig. 2. Fig. 3 is a view of the spindle; and Fig. 4 is a sectional view of the same, showing the location of the wire springs.

In the drawings, A is the spindle. B is the sleeve, secured to the spindle and provided with

the whirl B'; and C is the bolster-case, in which the bolster D is secured by a ball and socket, so as to yield to the motion of the spindle. The bolster D is provided with the ball *d*, 40 which rests in a curved seat in the bolster-case.

e e are bent wire springs interposed between the bolster and the bolster-case, so as to form a yielding resistance to the oscillation of the bolster on the ball-and-socket support. These 45 wire springs can be cheaply made, are easily secured, and as they extend from the ball to the end of the bolster, or about half the length of the bolster, they are stiffer and form a better support for the bolster than springs as 50 heretofore made, extending from end to end of the bolster. By the use of these springs *e e*, with the bolster D, supported near the middle of its length by the ball *d*, wabbling or vibratory movement of the spindle is almost entirely 55 avoided, and while the spindle and bolster are free to adjust themselves to the axial center of the load, the springs counteract this motion and limit the oscillation of the bolster.

Having thus described my invention, I claim 60 as new and desire to secure by Letters Patent—

The combination, with the spindle A, the sleeve-whirl B, and bolster-case C, of the bolster D, provided with the ball *d*, and the wire springs *e e*, secured to the ball *d* and resting in 65 notches in the bolster end, constructed to limit the oscillation of the bolster, as and for the purpose set forth.

THOMAS MAYOR.
